DESIGN FOR A BROILER GRILL

Stanley H. Hobson, Rockford, Ill., assignor to Geo. D. Roper Corporation, Rockford, Ill., a corporation of Illinois

Application September 1, 1939, Serial No. 87,008

Term of patent 7 years

To all whom it may concern:

Be it known that I, Stanley H. Hobson, a citizen of the United States, residing at Rockford, in the county of Winnebago and State of Illinois, have invented a new, original, and ornamental Design for a Broiler Grill, of which the following is a specification, reference being had to the accompanying drawing, forming part thereof.

In the drawing:

Fig. 1 is a perspective view of a broiler grill showing my new design;

Fig. 2 is a plan view of said grill; and

Figs. 3 and 4 are sections taken on the correspondingly numbered lines of Fig. 2.

I claim:

The ornamental design for a broiler grill, substantially as shown.

STANLEY H. HOBSON.
